DESIGN FOR A COFFEE BREWER

Harold L. Frick, Detroit, Mich., assignor to Bendix
Aviation Corporation, Detroit, Mich., a corpora-
tion of Delaware

Application February 19, 1944, Serial No. 112,646

Term of patent 14 years

(Cl. D44—26)

To all whom it may concern:

Be it known that I, Harold L. Frick, a citizen
of the United States, residing at Detroit, in the
county of Wayne and State of Michigan, have
invented a new, original, and ornamental De-
sign for a Coffee Brewer, of which the following
is a specification, reference being had to the ac-
companying drawing, forming part thereof.

The single figure is an elevational view of the
coffee brewer showing my design.

The coffee brewer is round, and therefore a
diametrically opposite view of that shown would
be identical.

I claim:

The ornamental design for a coffee brewer, as
shown and described.

HAROLD L. FRICK.
